PILE WIRE

Oliver J. Pickard and Fred Pickard,
Philadelphia, Pa.

Application June 28, 1934, Serial No. 732,934

1 Claim. (Cl. 139—44)

This invention relates to improvements in pile wires of the detachable cutter blade type, and a principal object of the invention is to provide a wire of that character having novel means for facilitating the insertion and detachment of the cutting blade.

The invention further resides in the novel structural features hereinafter set forth and illustrated in the attached drawing, in which:

10 Figure 1 is a side elevational view of the blade-receiving end of a pile wire made in accordance with our invention;

15 Figs. 2 and 3 are detached side elevational views of the elements of the blade-receiving end of the wire;

Fig. 4 is a sectional view on the line 4—4, Fig. 3, and

20 Fig. 5 is a view in perspective of the blade-receiving end of the wire illustrating the method of inserting and withdrawing the blade.

With reference to the drawing, the wire comprises an end portion 1 which in the present instance is attached by brazing to the body portion 2 of the wire. The end portion 1 is formed in the 25 present instance of a filler piece 3 formed as shown in Fig. 2 and a U-shaped envelope 4 shown in Figs. 3 and 4. In assembly, the piece 3 fits into the envelope 4 and is welded or otherwise secured to the latter. The combined thicknesses of the double wall of the envelope 4 and of the piece 3 are substantially the same as the normal thickness of the body 2 of the pile wire. By 30 reason of the recessed formation of the upper edge of the filler piece 3, as shown in Fig. 2, the assembly provides a pocket 5 for reception of a cutting blade 6, and this pocket as shown in Fig. 1 is undercut at both ends for the purpose of retaining and of preventing accidental displacement of the blade 6 after the latter has been 35 inserted in the manner hereinafter set forth.

As shown in Figs. 1, 3 and 5, one side of the envelope 4 is provided with a substantially V-shaped incision 7 providing a flap or tongue 8 which may be flexed outwardly as shown in Fig. 5 to afford access to the blade-receiving pocket 5. The diagonal forward end of this tongue lies opposite the corresponding undercut end of the pocket 5, while the lower edge of the tongue lies at the bottom of the said pocket, so that when the 45 blade 6, which is formed at its ends to neatly fit the undercut ends of the pocket, is slid into place

through the access opening afforded by the tongue 8, it slips neatly into the pocket 5 with its inclined ends in engagement with the correspondingly formed undercut ends of the pocket. The tongue 8 then exerts a resilient pressure against the side of the blade holding it in position in the pocket and preventing accidental displacement.

It will be noted that the lower attenuated end of the tongue 8 is cut away at 9 to provide an opening for insertion of a suitable pointed instrument for flexing the tongue 8 outwardly when the blade 6 is to be withdrawn from the pocket, the normal flexibility of the blade permitting displacement of the end laterally from under the contiguous inclined end of the pocket 15 so that the blade may be readily withdrawn. In inserting the blade, the pointed smaller end of the latter may be inserted under the end of the tongue, and by simple pressure slid into the pocket until the opposite end of the blade slips 20 under the undercut shoulder in the filler piece 3.

In the present instance, we have shown the filler piece 3 provided with an auxiliary cutting edge 10 which in the event that the main blade 6 is broken will be effective to cut the pile loop. 25 This auxiliary blade is not essential and may be eliminated where desired. There may be a considerable modification of the structure herein illustrated and described without departure from the invention as defined in the appended claim. 30

We claim:

A pile wire comprising a substantially U-shaped end portion, and a filler piece secured between the sides of said U-shaped end portion and being recessed at the top to afford a pocket 35 for reception of a primary cutting blade, the end of said filler piece adjoining the extremity of the wire being of increased height to provide a projection at the upper edge of the wire sharpened at the inner side and constituting an auxiliary 40 cutting blade, the ends of said pocket being undercut to prevent retraction of said primary blade from the top of the pocket, a section of one side wall of said U-shaped portion being partially severed to provide an integral flexible tongue 45 displaceable from the normal plane to afford access to said pocket for insertion and withdrawal of said primary blade.

OLIVER J. PICKARD.
